WALL PLAQUE PLANTER

Joseph Swbado, Toledo, Ohio

Application September 7, 1954, Serial No. 32,176

Term of patent 14 years

(Cl. D35—3)

FIG. 1.

FIG. 2.

FIG. 3.

FIG. 4.

To all whom it may concern:

Be it known that I, Joseph Swbado, have invented a new, original, and ornamental Design for a Wall Plaque Planter, of which the following is a specification, reference being had to the accompanying drawing, forming a part hereof.

I claim:

The ornamental design for a wall plaque planter, as shown.
